VENDING MACHINE FOR REFRIGERATED ARTICLES

Charles F. Wood, Los Angeles, Calif.

Application May 16, 1938; Serial No. 208,207

1 Claim. (Cl. 312—36)

This invention relates to a vending machine for vending refrigerated articles such as for example, small packaged bars of ice cream.

In attempts heretofore made to devise a vending machine for vending refrigerated articles of that character considerable difficulty has been experienced in being able to deliver a properly refrigerated package. Vending machines heretofore devised have held a suitable supply of the refrigerated articles which are delivered from the machine following the insertion of a coin. When a considerable time elapses between consecutive sales by the machine it has been generally found that the first one or more articles delivered from the machine are usually soft. It is, of course, highly desirable to be able to deliver a refrigerated commodity which will be hard or properly refrigerated at all times, and although a considerable time may elapse between consecutive sales, the first article delivered after an elapse of time will be delivered in proper condition.

I have discovered that the reason for the tendency for the article that is to be next delivered from a vending machine to warm up or soften up is due to two important features of the construction of the vending machine. In machines heretofore designed to vend refrigerated articles, the supply of articles to be vended is usually maintained in a refrigerated chamber and kept in stacked position therein. Frequently, there is a pocket or a depression in the bottom surface of the storage chamber in which the lowermost article of the stack, which is the next article to be delivered, is allowed to remain until the next sale. Sometimes the sides of the lowermost article or that article which is next to be delivered are enclosed by the structure of the vending machine. Either design is detrimental to the preserving of the lowermost article of the stack in proper refrigerated condition. If a pocket is formed in the bottom of the storage chamber within which the lowermost article is disposed, I find that cold air in the storage chamber does not enter into or settle in the pocket as would be expected but that instead, the air in the storage chamber, in circulating therein, passes over the top of the pocket. Under such circumstances, while the air in the main portion of the storage chamber may be many degrees below freezing, the temperature in the pocket is not sufficient to keep the refrigerated article in a properly refrigerated or salable condition.

Where the lowermost article of the stack or supply is largely surrounded by the vending ma-

chine structure, the surrounding structure has the tendency of protecting the article from the cold air circulating in the storage chamber and this prevents the lowermost article of the stack, or that article which is next to be sold, from being maintained in proper condition.

The second feature of design of the vending machine that has the effect of warming up or softening up that article that is next to be sold resides in the fact that the withdrawing mechanism is usually operated by a metal handle which serves to open a door from the storage chamber and to eject or discharge the lowermost article from the stack. When the handle extends through the door or is so designed that there is a direct metallic connection between the inside face of the door and the external handle, I find that a remarkable amount of heat is transferred through the handle and the metallic connection by conduction. The heat thus conducted to the interior of the storage chamber from the handle is also effective to cause the lowermost article of the stack to warm up or soften up.

It is an object of the present invention to provide an improved vending machine for vending refrigerated articles wherein the supply of articles to be sold is kept in stack form in the storage chamber and the storage chamber is so designed as to avoid pockets at the bottom thereof and to be conducive to the development of circulation of cold air in the storage chamber so that the cold air may circulate freely and rapidly beneath the lowermost article of the stack against the major portions of its sides and its bottom. Thus, if cold air may circulate quite freely around the lowermost article that article which is next to be vended is usually the coldest, firmest, and crispest article of the entire stack. In this way, even though considerable time may elapse between consecutive sales, the first article delivered will be in a good salable condition.

With the foregoing and other objects in view, which will be made manifest in the following detailed description and specifically pointed out in the appended claim, reference is had to the accompanying drawings for an illustrative embodiment of the invention, wherein:

Figure 1 is a view in front elevation of the improved vending machine, the door being broken away to show the guides for the stacks of articles inside the storage chamber;

Fig. 2 is a view in side elevation of the vending machine;

Fig. 3 is a partial vertical section taken sub-

stantially upon the line 3—3 upon Fig. 1 in the direction indicated;

Fig. 4 is a horizontal section taken substantially upon the line 4—4 upon Fig. 3;

5 Fig. 5 is a partial view in perspective, parts being broken away and shown in section of the withdrawing mechanism and the associated door which is utilized to withdraw an article from the stack or source of supply following the insertion of a coin into the machine;

10 Fig. 6 is a plan view illustrating a detail of construction; and

Fig. 7 is a partial view in vertical section taken substantially upon the line 7—7 upon Fig. 6.

15 Referring to the accompanying drawings wherein similar reference characters designate similar parts throughout, the improved vending machine comprises a suitable cabinet which provides a lower compressor compartment, generally designated at 10, and an upper storage compartment, generally designated at 11. In the lower compartment 10 there may be disposed any suitable form of motor-driven compressor or the equivalent for compressing a refrigerating medium which expands within a cooling coil 12 disposed adjacent the back of the storage chamber 11. Any suitable form of cooling mechanism may be employed for refrigerating the storage chamber 11. In the preferred form of construction, however, the expansion coil is preferably arranged at the back of the storage chamber and above the bottom thereof.

20 The storage chamber has its front wall normally closed by a hinged door 14 which is locked in closed position by means of a suitable latch 15 provided with a lock 16. In the forward wall of the cabinet there is also provided a suitable opening 17 through which the articles purchased are discharged. In back of this opening, there is 25 formed an inclined chute 18 which may receive articles from any of the stacks in the storage chamber. The articles, when released and removed from the storage chamber, slide downwardly and forwardly on the chute 18 and are removed by the purchaser through the opening 17.

25 In the front wall of the cabinet also there is disposed a coin-receiving opening 19 from which a coin deposited in the machine passes to a suitable coin mechanism, the cover for which is designated at 20. The particular form of coin mechanism forms no part of the present invention and therefore is not illustrated herein. In the preferred embodiment, however, it includes a suitable slug ejector.

30 The function of the coin mechanism is such that when a coin is deposited in the opening 19, rod 21 (see Fig. 6) is released so that this rod may be moved forwardly. The rod 21 is connected to a bellcrank or cam 22 pivoted at 23. 35 When rod 21 is released the bellcrank or cam 22 may be rotated in a clockwise direction.

35 The vending machine is equipped with one or more reciprocating handles indicated at 25. I have illustrated these handles as being four in number, there being one handle for each stack of articles of varying flavors stored within the storage chamber 11. Associated with each handle is a door, the details of which will hereinafter be more fully described.

40 In operation, when a coin is deposited in the coin slot 19 the purchaser then selects the proper handle associated with the flavor of the article that he desires and pulls that handle forwardly. This effects a discharge of the lowermost article 45 of the stack with which the handle is associated

from the storage chamber 11 and the article is thus recovered through the opening 17 previously described.

45 The handles are attached to suitable pull rods 25a which slidably extend through a transversely extending bar 26. The top of each pull rod 25a is recessed as at 27 to accommodate cooperating plates 28. When any handle 25 is pulled forwardly, the knife edge at 29 engages the left-hand end of its adjacent cooperating bar or 50 plate 28 and shifts the same from left to right. When the plate or plates 28 move toward the right as the pull rod 25a is pulled forwardly, then bellcrank 22 is moved in a clockwise direction, this being permitted by the release of rod 55 21 on the insertion of a coin. When any pull rod is pulled forwardly, it prevents all plates 28 to the left of the pull rod from sliding toward the right. Consequently, no pull rod to the left of that which has been pulled forwardly can be 60 pulled to withdraw an article from its stack. Those plates 28 which are to the right of the pull rod are shifted thereby a distance equal to the width of the pull rod and these consequently, lock all pull rods to the right against being 65 pulled forwardly. Consequently, when one coin is deposited only one pull rod may be pulled forwardly to release an article from its stack.

70 When the rod 21 is moved forwardly it has the effect of releasing and clearing the coin-controlled mechanism so that when the pull rod 25a is returned to its initial position the machine is then in condition to receive a subsequent coin and to vend a subsequent article.

Upon the release of the pull rod it is returned 75 to its initial position by means of a cable 57 and a spring 58 and the bellcrank 22 and the plates 28 are returned to their initial positions by a spring, not shown, which is operable thereon.

By the above-described construction, it is possible on the insertion of a single coin to procure one article of any desired flavor but it is impossible to pull forwardly more than one handle 80 upon the insertion of a single coin.

85 Within the storage chamber, I have illustrated 45 four stacks of packaged bars of ice cream, one stack being directly in back of each handle 25. These stacks are supported within suitable guides as shown on Fig. 4, wherein each guide has side portions 30 and 31 engageable with the ends of 50 the articles of the stack and rear portions 32 and 33 engageable with the rear sides of the articles of the stack. The forward sides of the articles of the stack are engaged by strips or flanges 34 and 35 which are hingedly connected as at 36 and 55 37, respectively, to the forward outwardly bent portions to the sides 30 and 31. These strips or flanges can be thus swung forwardly to open the guides for the stacks their complete width to enable refilling each guide by merely moving a 60 stack of articles to be sold into its respective guide means through the open front afforded by the opening of the strips or flanges 34 and 35. Locking bars 38 are pivotally connected to each flange or strip 35 and are engageable with studs 65 on each strip or flange 34 to lock these hinged flanges in closed position, as shown in Figs. 1 and 3. The guides terminate at their lower ends a short distance above rails 39 and 40 which are supported above the bottom of the storage 70 chamber 11. These rails 39 and 40 are relatively narrow as compared with the length of the articles and are spaced apart a distance approximately equal to the length of each article or package in the stack so that air may freely cir- 75

culate against a relatively large area of the bottom of the lowermost package of the stack through the intervening space 41.

It will be noted that an apex is formed at the forward ends of adjacent guides and that the strips or flanges 34 and 35 are hingedly attached to these apices. Thus the forward side of each guide has a flared entrance which facilitates the insertion of a renewing stack of articles.

The rails 39 and 40 extend from adjacent the forward side of the storage chamber to adjacent the back thereof and slidably a drawer-like ejecting mechanism which includes a pair of side bars 42 and 43 preferably constructed from strips of relatively thin sheet metal having a width approximately equal to the vertical height of one of the articles in the stack, the bars 42 and 43 being joined at their rear ends by a rear member 44 adjacent which there are disposed spacers 45 and 46. The side bars 42 and 43 and the spacers 45 and 46 are of approximately the same width as the rails 39 and 40 and disposed beneath a roller 47 rotatably mounted on brackets 48 rigidly secured to the rails 39 and 40, respectively, the brackets 48 preventing lateral displacement of the drawer-like ejector from the rails while the roller 47 extending across the side bars 42 and 43 rotatably engages these bars and the spacers 45 and 46 to prevent inadvertent lifting of the drawer-like ejector from the rails 39 and 40. The spacers 45 and 46 are of the same height as the side bars and this height of the side bars is substantially equal to the thickness (the vertical height) of a package or article. The forward ends of the side bars are connected to a rubber projection 49 formed on the rear side of each door 50 which opens the storage chamber. This door preferably comprises soft and hard rubber integrally molded. The projection 49 is preferably formed of hard rubber and the balance soft rubber. The box-like structure formed by the rubber is filled with a suitable heat insulating material indicated at 50a. Each box-like door 50 is designed to enter and seat in a door seat 51 formed of hard rubber. In the preferred form of construction the projection 49 enters and fills the opening 52 at the back of the door seat. The top of the box-like structure slides beneath the top of the seat and at its forward end is provided with a soft rubber lip 53 engageable with the forward edge of the top of the door seat. The side walls of the door seat are downwardly and rearwardly inclined as indicated at 54 and a corresponding shoulder 55 which is of soft rubber and which is formed on the sides of the door is engageable therewith. Thus, when the door is in seated or closed position, projection 49 fills the opening 52 in the door seat and double seals are formed, one being at the front and the other being at the back of the door preventing ingress of heat and air to the storage chamber. The rear end of each pull rod 25a is attached to its respective door such as by screws 56. These screws, as will be noted from Fig. 4, do not extend entirely through the projection 49. Thus, there is no direct metallic connection between any handle 25 and the interior of the storage chamber nor is there any metal connection exposed on the exterior of the cabinet which is also exposed on the interior of the door. Consequently, heat may not be conducted from the exterior of the cabinet to the interior to warm or soften the lowermost block of any stack that is about to be discharged.

A cable 57 is attached to the rear transverse

member 44 and is trained over a pulley 58 to a spring 59 urging the slide formed by the side members 42 and 43 into normal rearmost position wherein the door is closed.

The operation and advantages of the above-described construction are as follows: When a coin is deposited in the coin slot 19, rod 21 is released. Any handle 25 may then be pulled forwardly but by virtue of the construction illustrated in Figs 6 and 7, no more than one handle 10 may be pulled forwardly at one time. On pulling the handle forwardly, the pull rod 25a shifts the door into open or dotted line position illustrated in Fig. 3. The lowermost package or article of the stack which is resting on the rails 39 15 and 40 between side members 42 and 43, is slid forwardly through the opening in the door seat which is vacated by projection 49. It then falls onto chute 18 and is removed by the purchaser through the opening 17. On release of the 20 handle, spring 59 returns the slide and door into the initial position.

When the slide is in its forward position the spacers 45 and 46 slide beneath the stack to occupy the position previously occupied by the 25 lowermost article. When the spacers 45 and 46 are returned to their normal position the stack is allowed to fall, thus depositing a succeeding package or article of the stack on rails 39 and 40 between the side members 42 and 43. 30

As indicated by arrow on Fig. 3, the arrangement of the cooling coils at the back of the storage chamber causes a circulation of air to be generated within the storage chamber in the manner indicated. The cold air descending from 35 the cooling coils may flow downwardly between the spacers 45 and 46 against the rear side of the package or article then beneath the bottom surface of the lowermost package or article which is supported on rails 39 and 40, and then upwardly 40 between the forward side of the lowermost package or article and projection 49. Thus three sides of the package next to be vended are subjected to the cooling effect of the cold air. As 45 the sides 42 and 43 are formed of metal, they do not insulate the ends of the package next to be vended from the cooling effect of this cold air. Consequently, with the present machine, even though considerable time may elapse between succeeding sales, the lowermost article will 50 always be delivered in a crisp, hard condition. It will be noted that the lowermost article of each 55 stack is not disposed within any depression or cavity at the bottom of the storage chamber which would form a space of quiescent air that would retard the free circulation of cold air around the lowermost article. Consequently, with the present construction the article to be vended next is usually the coldest article of the entire supply. 60

In order to prevent operation of any handle 25 when its stack has become exhausted, I prefer to position a wooden block 60 of the same size and shape as an article of the stack with the exception that it is considerably thicker than an 65 article on top of the entire stack. When all articles of the stack are removed, this block then enters between the sides 42 and 43 but as it is somewhat higher than the height of the opening in the door seat normally occupied by projection 49, it prevents operation of its corresponding pull rod. 70

When it is desired to refill the cabinet this is easily accomplished by opening the door 14, lifting the locking bars 38 and swinging outwardly 75

strips or flanges 34 and 35. These open the forward side of each guide means entirely so that a replacing stack may be bodily shifted into the guide means. In this way the cabinet may be 5 quickly refilled with a minimum loss of refrigeration in the storage cabinet.

Various changes may be made in the details of construction without departing from the spirit or scope of the invention as defined by the 10 appended claim.

I claim:

In a vending machine for vending refrigerated articles of substantially uniform shape and size, having a storage chamber and an exit 15 through which articles may be vended one at a time, the combination therewith of a channel forming means defining a vertically extending channel for receiving and holding a stack of the articles piled one upon the other and having a 20 horizontal cross section substantially equal to the horizontal cross section of one of the articles, said channel means terminating at its lower end in spaced relation to the bottom of said stack, a pair of rails extending across the lower end 25 of said channel and spaced below the lower end thereof by a distance substantially equal to the vertical height of one of the articles in the stack, said rails being adapted to engage the lower face of the lowermost article to support the stack in

said channel, the contacting face of each of said rails being so narrow as to cover but a small fraction of the area of the lower face of said article, ejecting means for ejecting said articles one by one from the stack comprising a drawer-like member disposed on said rails and slideable from a normal inner position to an outer ejecting position and having a pair of side bars so spaced from each other as to engage only the end faces of the lowermost article, and a pair of spacer 10 blocks of less length than said bars and rails, one secured to each side bar, each of said spacer blocks having a vertical height equal to the height of said side bar and a width not to exceed the width of one of said rails, the front ends of 15 said spacer blocks in the normal inner position of the drawer-like member terminating at points in vertical alignment with the rear of the channel forming means whereby to permit the lowermost article of the stack to drop onto said rails 20 and to support the next lowermost article as the lowermost article is ejected from the stack, the construction being such that when said ejector means is in either of its positions a relatively large area of the lowest article is free from engagement with the respective supporting means, and means to guidingly retain said drawer-like ejector member on said rails during movement.

CHAS. F. WOOD.
